UNITED STATES PATENT OFFICE.

THOMAS HUNT CLARKE, OF CAMDEN, NEW JERSEY.

GAGE FOR CUTTING-BITS.

1,190,110.

Specification of Letters Patent.

Patented July 4, 1916.

Application filed September 4, 1914. Serial No. 860,239.

To all whom it may concern:

Be it known that I, THOMAS H. CLARKE, a citizen of the United States, residing at Camden, in the county of Camden and State of New Jersey, have invented new and useful Improvements in Gages for Cutting-Bits, of which the following is a specification.

This invention relates to improvements in 10 gages for cutting bits and has particular application to an adjustable bit carried gage.

In carrying out the present invention, it 15 is my purpose to provide a gage for cutting bits whereby the depth that the bit enters the hole being drilled may be regulated so that the cutting end of the bit will penetrate the material to a predetermined degree only.

It is also my purpose to provide a gage 20 which will be found especially useful with cutting bits for drilling screw holes whereby the depth of the hole will be regulated in accordance with the length of the screw.

Furthermore, I aim to provide a gage of 25 the class described whereby the outer end wall of the hole will be countersunk to receive the head of the screw so that the outer face of such head will lie flush with the wood, metal or other material in which the hole is drilled.

30 With the above and other objects in view, the invention consists in the construction, combination and arrangement of parts hereinafter set forth in and falling within the scope of the claims.

35 In the accompanying drawing, Figure 1 is a view in side elevation of a drill bit and brace therefor, the bit being equipped with a gage constructed in accordance with the present invention. Fig. 2 is a view in side 40 elevation of the gage showing the same applied to the bit. Fig. 3 is a vertical sectional view through the gage and adjacent portion of the bit. Fig. 4 is a cross sectional view on the line 4-4 of Fig. 3. Fig. 5 is a 45 perspective view of one part of the gage. Fig. 6 is a like view of the companion part. Fig. 7 is a similar view of the cutting bit removed from the brace.

Referring now to the drawing in detail, 1 50 designates a breast brace having one end thereof equipped with the usual chuck 2, while 3 indicates a drill bit. In the present instance, the bit 3 comprises a main body portion 4 having one end portion thereof 55 square in cross section and tapering toward the outer end thereof as at 4' and provided,

at the corners, with cutting teeth 5, while the extremity is formed with the usual cutting threads 6 adapted to enter the material in advance of the teeth 5 so that the last- 60 mentioned teeth may form threads in the wall of the opening being drilled. The chuck end of the body portion 4 is reduced to provide a shank 7 designed to enter the chuck of the brace, while formed in one side 65 wall of the main body portion 4 of the bit adjacent to the chuck end thereof is a longitudinal groove 8 and disposed below the groove 8 and spaced apart vertically are notches 9. The opposite side of the main 70 body portion of the bit behind the groove 8 and series of notches 9 is formed with two series of notches 10, 10 respectively.

In the present instance, my improved gage 75 comprises a collar 11 surrounding the main body portion of the bit adjacent to the chuck end thereof and substantially square in cross section. Formed integral with one edge of one side of the collar 11 and projecting toward the cutting end of the bit parallel with 80 the main body portion thereof is a plate 12 having the lower end thereof formed with outwardly extending legs 13, 13 contiguous to the longitudinal edges of the plate and spaced apart in parallelism, while formed 85 in the plate 12 approximately centrally thereof adjacent to the last-mentioned end thereof is an opening 14. Surrounding the main body portion of the cutting bit is a second collar 15 substantially square in cross 90 section and spaced apart from the collar 11 and formed integral with one edge of one side of the collar 15 and projecting toward the chuck end of the bit is a plate 16 overlying the plate 12 and in face to face contact therewith, while formed on the chuck end of the plate 16 contiguous to the longitudinal edges of such plate are legs 17, 17 spaced apart in parallelism and fitting within grooves 18, 18 respectively formed in the 100 adjacent side of the sleeve 11, the legs 13 on the plate 12 fitting within grooves 19, 19 respectively formed in the inner surface of the adjacent side of the collar 15. Formed 105 in the plate 16 and registering with the opening 14 in the plate 12 is a longitudinal slot 20 and passed through the opening 14 and slot 20 is a headed screw 21 having the head countersunk in the opening 14 and the shank projecting through the slot 20 and 110 threaded to receive a thumb nut 22. Disposed within the collar 11 and encircling the

adjacent portion of the bit is a bushing 23 of a cross sectional configuration corresponding to that of the bore in the collar and the bit and formed in opposite walls of the 5 collar 11 and bushing 23 are alining openings into which are threaded set screws 24, 24 having the inner ends thereof engaging the notches 10 and groove 8 respectively whereby the collar 11 will be held against 10 longitudinal movement along the bit. When the nut 22 is tightened, the confronting faces of the plates 12 and 16 are held in frictional engagement, thereby preventing relative longitudinal movement of such 15 plates and the collar 11.

Surrounding the main body portion 4 of the bit is a sleeve 25 having one end thereof disposed within the collar 15 and the opposite end projecting toward the cutting end 20 of the bit. Formed on the sleeve 25 approximately centrally thereof is an outwardly projecting flange 26 extending around the sleeve and abutting the adjacent end of the collar 15, while disposed within 25 the collar 15 between the inner surface of the latter and the outer surface of the sleeve 25 is a bushing 27 of a cross sectional configuration corresponding to that of the collar and threaded into alining openings in the 30 collar, bushing and sleeve are set screws 28, 28 having the inner ends thereof capable of engaging in one of the notches in the series 9 and 10 respectively so as to assure the holding of the gage against longitudinal 35 movement on the bit. The outer edge of the sleeve 25 is formed with cutting teeth 29 spaced apart equal distances and lying against the adjacent portion of the bit so as to engage the outer end of the opening 40 drilled by the bit to countersink the same. In the present instance, the longitudinal side walls of the slot 20 are serrated as at 30 and the serrations upon one edge aline with those on the opposite edge to form, in effect, openings capable of interchangeable 45 registration with the opening 14.

In practice, the chuck end of the bit is secured within the chuck 2 in the usual well known manner and the set screws 24 and 28 50 loosened so that the gage may be adjusted, as an entirety, longitudinally of the bit and locked in the desired adjusted position. Should it be desired to obtain a very fine 55 adjustment, the set screws 28 remain loose, while the set screws 24 are tightened and the thumb nut 22 is loosened so that the collar 15 carrying the sleeve 25 may be adjusted upon the bit relatively to the collar 11, the outer edge of the sleeve 25 being disposed a 60 distance from the cutting end of the bit equal to the depth of the hole to be cut or drilled. As the bit penetrates the material to the required depth the teeth 29 countersink the

outer end of the hole. In the use of the bit 3, the cutting end 6 thereof penetrates the 65 material, while the teeth 5 at the corners of the tapered cutting end portion of the bit act upon the wall of the opening to form screw threads therein so that a screw may be threaded into the opening formed by the cutting bit with ease and facility. 70

From the foregoing description taken in connection with the accompanying drawing, the construction, mode of operation and manner of employing my improved gage will 75 be readily apparent. It will be seen that I have provided a gage whereby the depth that the cutting bit enters the hole being drilled may be limited and whereby the outer end of such hole will be countersunk. 80

I claim:

1. A gage for cutting bits comprising a collar adapted to surround the bit adjacent the brace end thereof, a plate depending from the inner surface of one side of the collar, the outer surface of said side having spaced vertical grooves, a second collar adapted to surround the bit below the first collar and at a remote point therefrom, a plate rising from the outer surface of one 85 side of the second collar, the inner surface of said side having spaced vertical grooves, said plates being arranged in face to face contact and slidably adjustable relatively, means for holding said plates fixed relatively, spaced parallel legs projecting from the free end of each of said plates contiguous to the longitudinal edges thereof, the legs of one plate being arranged in the 90 said grooves in the collar carried by the other plate, and means for holding the collars fixed upon said bit. 95

2. A gage for cutting bits comprising a collar adapted to surround the bit adjacent the brace end thereof, a plate depending from one side of the collar, a sleeve surrounding the bit adjacent the cutting end thereof, a laterally disposed flange formed on the upper end of said sleeve, cutting teeth formed on the lower end thereof, a 110 bushing rising from said flange in alignment with said sleeve and embracing said bit, a second collar surrounding said bushing and resting upon said flange, a plate extending upwardly from the second mentioned collar in face to face contact with the first mentioned plate, means for holding said collars fixed relatively, said plates being slidably adjustable, and means for holding said plates in fixed relation. 115

In testimony whereof I affix my signature in presence of two witnesses.

THOMAS HUNT CLARKE.
